[57] CLAIM

The original design for a combined stadium seat and tray, as shown and described.

DESCRIPTION

FIG. 1 is a top plan view of a combined stadium seat and tray showing our new design;

FIG. 2 is a front elevational view;

FIG. 3 is a left side elevational view, the right side being a mirror image thereof;

FIG. 4 is a bottom plan view;

FIG. 5 is a rear elevational view; and

FIG. 6 is a sectional view taken along section line 6—6 of FIG. 1.

FIG. 1

FIG. 2

FIG. 3
